AND GRINDER COMPANY, OF FANEUIL, MASSACHUSETTS, A CORPORATION OF
MASSACHUSETTS.

FEED MECHANISM.

1,299,716.

Specification of Letters Patent.

Patented Apr. 8, 1919.

Application filed April 8, 1918. Serial No. 227,408.

To all whom it may concern:

Be it known that I, FREDERICK H. HALSTEAD, a citizen of the United States, and a resident of Boston, county of Suffolk, and State of Massachusetts, have invented an Improvement in Feed Mechanisms, of which the following description, in connection with the accompanying drawings, is a specification, like characters on the drawings representing like parts.

This invention pertains to improvements in feed mechanisms, and more particularly, though not exclusively, to automatic feed-reducing mechanisms for use in connection with machine tools.

I have elected to show and describe one embodiment of a preferred form of my invention in connection with a grinder which may resemble somewhat the oscillating grinder for grinding ball races shown in my co-pending application, Serial No. 221,954, filed March 12, 1918.

In the drawings:

Figure 1 is a side elevation of a grinder provided with a preferred form of my improvement in feed-reducing mechanisms:

Fig. 2 is an enlarged elevation, partly in section, showing a detail of the feed mechanism;

Fig. 3 is a section, partly in elevation, on the line 3-3 of Fig. 2; and

Fig. 4 is an end elevation of that portion of the feed mechanism shown in Fig. 2.

In Fig. 1 I have shown my improved feed mechanism in connection with an oscillating grinder in which 5 is the tool spindle and 6 is the work chuck carried by the work spindle. The work is shown as carried by an oscillatory support 7, while the tool spindle 5 is carried by a tool-head 8 which is adapted to be fed toward the work by movement along a feed slide 9, all in substantial accordance with my co-pending application.

The before-described mechanism constitutes one form of machine tool in which the work and tool are relatively traversed while one is fed relative to the other by intermittent feed mechanism.

In the preferred form of my invention selected for illustrative purposes, the movable slide 9 is fed relative to the stationary slide 10 by a feed screw adapted to be intermittently rotated by a ratchet 11, prefer-

ably through intermediate reversing gearing, as shown in my co-pending application before referred to.

The ratchet 11 may receive its movement from a pawl 12, which is preferably moved to and fro through a predetermined path of movement by any suitable mechanism, herein shown as the lever 13 corresponding to the similar lever in my co-pending application, and acting through a reciprocatory awl-carrying rod 14 which may be, and preferably is, provided with a feed-limiting nut 15 adapted to abut against a stationary support 16 and to limit the downward movement of the pawl-carrying rod 14. In the preferred form of my invention, the rod 14 is positively moved in an upward direction by the lever 13 and resiliently moved in a downward direction by the opposed resilient means or spring 17. The pawl 12 is preferably resiliently urged toward the ratchet 11 by a spring 18 carried by the reciprocatory pawl-carrying rod 14.

I will now describe the preferred form of means for gradually reducing the amount of rotary feeding movement imparted to the ratchet 11 by the pawl 12. The shaft 19, on which the ratchet 11 is carried, is preferably rotatably mounted so that it can turn with the ratchet 11. Co-axial with the shaft 19 I preferably provide a cam element, herein shown as the sleeve 20, having a thread or track 21 cut in the face thereof. The cam element 20 is preferably rotatable about the shaft 19, and preferably cooperates with clutch means so that said cam element can be secured to the shaft 19 at any desired point. As the ratchet 11 may be, and preferably is, keyed or otherwise attached to the shaft 19, it follows that the cam element 20 can be adjusted to any desired position relative to the ratchet 11. The preferred form of clutch means comprises a split ring 21' which is held stationary relative to the ratchet 11 and shaft 19 by a pin 22, and which is adapted to be spread by a wedge element 23 to expansibly engage the interior of the cam element 20. The wedge 23 is adapted to be moved to and fro by a conical tapered portion 24 on a rotatable stud 25, preferably threaded at its inner end 26 to the shaft 19, and preferably provided at an outer end with a thumb-nut 27.

Engaging the groove 21 in the cam ele-

ment 20 I preferably provide a pin 28 carried by a sliding, feed-controlling bar 29. The attachment between the pin 28 and feed-controlling bar 29 is preferably resilient, being provided with a spring 30 so that the pin 28 may be disengaged from the groove 21. The inner end of the feed-controlling bar 29 is preferably supported in slideable relation to a stationary portion of the machine by any suitable guiding means, herein shown as the pins 31 and 32 passing through a slot 34 in the feed-controlling bar 29. The opposite end of the feed-controlling bar preferably carries a relatively thin pawl-engaging portion 35, adapted to be interposed between the pawl 12 and the adjacent teeth of the ratchet 11 to limit and determine the point during the operative stroke of the pawl at which the point of the pawl shall engage the teeth of the ratchet 11, and therefore become operative to turn said ratchet 11. The pawl-engaging portion of the pawl-controlling element 29 may be beveled, as shown at 36, to provide a gradually decreasing feed, or said portion of said element may take any desired form which is necessary or desirable to provide any preferred rate of decrease of the feeding movement when the feed-controlling bar 29 is moved toward the ratchet 11 by the groove 21 acting against the pin 28 as the cam element 20 is rotated by the ratchet 11. The operation of the preferred form of my invention is as follows:—Where it is desired to provide a forward movement of the feed-controlling element 29 for each movement of the ratchet 11 the pin 28 is entered in the groove 21 and the machine is started in operation, thereby causing the pawl-carrying rod 14 to reciprocate and turn the ratchet 11. As the ratchet 11 is turned it turns the cam element 20 and the groove 21 in said cam element, acting through the pin 28, pushes the feed-controlling rod 29 toward the ratchet 11 so that the thin pawl-engaging portion of the feed-controlling element 29 passes between the pawl 12 and the adjacent portion of the ratchet 11, thereby causing the pawl to be held out of engagement with the adjacent teeth of the ratchet during a portion of the forward or operative movement of the pawl 12. That portion of the stroke of the pawl which is thus rendered inoperative will be determined by the contour of the surface 36 of the pawl-controlling element and, where a regularly beveled edge 36 is provided, as shown in the drawing, the amount of the stroke of the pawl which is rendered inoperative is progressively increased until, if desired, the entire stroke of the pawl 12 will have been rendered inoperative so that intermittent rotation of the ratchet 11 will cease, thereby stopping relative feeding movement of the work and tool.

Where it is desired to provide a constant rate of relatively slow feed followed by a gradual reduction, the feed-limiting nut 15 may be adjusted downwardly on the threads of the pawl-carrying rod 14 so that a comparatively limited range of movement will be imparted to the pawl-carrying rod 14 by the lever 13.

I may, if desired, provide a constant rate of feed followed by a gradually diminishing feed by withdrawing the pawl 28 from the groove 21 and setting the feed-controlling rod 29 at any desired point with the end of the pin 28 resting on the higher portion of the surface of the cam element 20. The cam 20 will not impart any longitudinal movement to the pawl-controlling element 29 until the pin 28 drops in the groove 21 because of ratchet-actuated rotation of the cam 20, after which the rate of feed will be progressively reduced and, if desired, entirely terminated by the automatic feed-reducing mechanism in the manner previously described.

I may, if desired, utilize the longitudinal movement of the feed-controlling element 29 to operate traverse stopping mechanism for stopping the relative traverse of work and tool at any desired point. This may be effected through mechanism resembling somewhat that shown in my co-pending application above referred to, and connected to a lever 37, which is preferably provided with an adjusting screw 38 and which functions in a manner similar to the corresponding lever and adjusting screw of said co-pending application. The movement of the lever 37 by the feed-controlling element 29 may be effected when the end 39 of said element presses against the end of the adjusting screw 38.

While I have shown and described a preferred form of one embodiment of my invention, it will be understood that major changes involving omission, substitution, alteration and reversal of parts, and even changes in the mode of operation, may be made without departing from the scope of my invention, which is best defined in the following claims.

Claims:

1. In a machine tool, feed mechanism comprising a pawl, means for imparting to said pawl a to-and-fro movement, a ratchet engaged by said pawl, and means driven at a rate slower than the periphery of said ratchet and adapted to control the effective periods of engagement of said pawl with said ratchet.

2. In a machine tool, feed mechanism comprising, in combination, a pawl, means for imparting a to-and-fro movement to said pawl, a ratchet wheel engaged by said pawl, and means actuated by movement of said ratchet, through interposed speed-reducing

means, for progressively diminishing the periods of engagement of said pawl with said ratchet.

3. In a machine tool, feed mechanism comprising, in combination, a ratchet, a pawl engaging said ratchet, and means movable transversely of the periphery of said ratchet for progressively reducing the periods of effective engagement of said ratchet by said 10 pawl.

4. In a machine tool, feed mechanism comprising, in combination, a ratchet, a pawl, a guard having an inclined edge, and means for progressively interposing said guard between said pawl and the adjacent portion of the periphery of said ratchet, thereby to control the feeding movement.

15 5. In a machine tool, feed mechanism comprising, in combination, a pawl, a ratchet

engaged thereby, cam means driven by said 20 ratchet, and a guard adapted to be moved by said cam means into interfering relation between said pawl and ratchet.

6. In a machine tool, feed mechanism comprising, in combination, a ratchet, a pawl, a 25 guard, means for advancing said guard in a direction substantially parallel to the axis of said ratchet into interfering relation between said pawl and ratchet, and means controlled by movement of said guard and co-operating parts for effecting stoppage of co-operating parts of the machine tool when feeding movement has progressed to a predetermined point.

In testimony whereof I have signed my 35 name to this specification.

FREDERICK H. HALSTEAD.
